WRINGER HEAD FOR WASHING MACHINES
William B. Beuscher, 5244 Mohawk Drive,
Shawnee Mission, Kans. 66205
Filed Jan. 11, 1965, Ser. No. 424,769
9 Claims. (Cl. 68—255)

This invention relates to new and useful improvements in wringer heads for washing machines, and has particular reference to the indexing and locking mechanisms of such wringer heads.

In washing machines of an ordinary household type, the wringer assembly is disposed over an open-topped tub or tank, being carried by a wringer head. Said wringer head is mounted at the upper end of a vertical power shaft disposed adjacent the side of the tub, and serves to transmit power from said shaft to the wringer rolls, which are usually horizontal. Said wringer head is provided with clutch means whereby the wringer rolls may be started, stopped and reversed. It is also provided with means whereby it may be pivoted about its vertical axis to position the rolls for conveniently transferring material being laundered from the washing machine tub to other tubs or containers adjacent the washing machine. It will be seen that the operating torque of the power shaft tends to rotate the wringer head about its vertical axis, with resultant danger of injury to persons standing nearby, as the head may be whipped about with very substantial power and force. Injuries from this cause, with resultant expensive lawsuits, are not infrequent. Accordingly, wringer heads of this type are commonly equipped with locking means for releasably securing it against rotation, said locking means being interconnected with the clutching means in such a manner that, at least nominally, the head cannot be clutched to drive the wringer rolls except when it is firmly locked against rotation.

Nevertheless, in a wringer head in very common usage, despite the fact that it is equipped with the above described safety feature, free swinging of the head about its vertical axis, with its resultant danger to nearby persons, can still occur under certain circumstances. Specifically, such free swinging can occur either when the head is clutched while positioned intermediate its normal index positions, or as a result of sticking or binding of certain parts, although the circumstances will be better described and more fully understood later in the following specification.

Accordingly, the principal object of the present invention is the provision, in a wringer head of the type described, of additional safety means which will positively prevent free or uncontrolled rotation of the head about its vertical axis under any and all circumstances.

Another object is the provision of a safety means of the type described which is entirely automatic in operation, requiring no attention from or manipulation by the user.

A still further object is the provision of safety means of the type described which not only arrests and prevents rotation of the wringer head about a vertical axis, but also tends to correct the malfunction which originally caused such rotation.

Other objects are simplicity and economy of construction, efficiency and dependability of operation, and adaptability for use with various types of washing machines.

With these objects in view, as well as other objects which will appear in the course of the specification, reference will be had to the accompanying drawing, wherein:

FIG. 1 is a vertical sectional view of a washing machine wringer head including safety means as contemplated by the present invention, including fragmentary

2

showings of adjacent portions of the washing machine, with parts left in elevation,

FIG. 2 is a sectional view taken on line II—II of FIG. 1,

5 FIG. 3 is a slightly irregular sectional view taken on line III—III of FIG. 1,

FIG. 4 is an enlarged sectional view taken on line IV—IV of FIG. 1, with parts left in elevation,

10 FIG. 5 is an enlarged sectional view taken on line V—V of FIG. 1,

FIG. 6 is a fragmentary sectional view taken on arcuate line VI—VI of FIG. 5, laid out in planar form,

15 FIG. 7 is a fragmentary sectional view taken on arcuate line VII—VII of FIG. 5, laid out in planar form, and showing one operable position of the safety device forming the central subject matter of the present invention,

FIG. 8 is a view similar to FIG. 7 but showing another operable position of the safety device,

20 FIG. 9 is a view similar to FIG. 5, but showing a slightly modified form of the invention,

FIG. 10 is a fragmentary sectional view taken on arcuate line X—X of FIG. 9, laid out in planar form, and

25 FIG. 11 is a view similar to FIG. 10, but showing the safety device in an operating position.

Like reference numerals apply to similar parts throughout the several views, and the numeral 2 applies generally to a washing machine of the ordinary wringer

30 type including an open-topped tub or tank 4 in which it will be understood there is usually an agitator member driven by an electric motor, neither being shown since they are not pertinent to the present invention. A

35 wringer drive shaft 6, having the form of a flat rectangular bar, extends vertically adjacent the side of tub 4, and is adapted to be rotatively driven by the same motor or other power unit which drives the agitator. Said drive

40 shaft is carried in a non-rotating tubular column 8 which extends above tub 4 and encloses the upper end of the drive shaft, and which is rigidly affixed adjacent its upper end in a bracket 10 mounted on the tub as by rivets 12.

45 A circular index plate 14 is rigidly and concentrically fixed to column 8 in spaced relation above bracket 10. As best shown in FIG. 5, said index plate is provided

50 with a plurality of notches 16 equally spaced about the periphery thereof. Eight notches are shown, though a larger or smaller number could be used if desired, an even number being preferred.

55 The wringer head, designated generally by the numeral 18, is rotatably mounted on the upwardly extended end portion of column 8, above index plate 14. Said wringer head includes a hollow metallic housing 19 having an inner end wall 20, outer end wall 22, a top wall 24, a

55 bottom wall 26, removable front and rear walls 28 and 30, and a tubular portion 32 extending downwardly from bottom wall 26, said tubular portion having at its lower end a cylindrical skirt 34 which normally encloses and extends slightly below index plate 14.

60 Coaxially with tubular portion 32 thereof, the housing is provided with an integral cylindrical post 36 which is axially bored from its lower end to form a socket 38 which fits rotatably over the upper end of column 8, whereby the wringer head may be rotated about its vertical axis and

65 may move longitudinally with respect to said axis. A finder button 40 is rigidly fixed in the housing member at the lower end thereof intermediate post 36 and skirt 34, being inserted tightly in a tubular support 42 formed integrally with the housing. Said finder button is of conical

70 form, tapering downwardly, and is adapted to rest by gravity selectively in any one of notches 16 of index plate 14, whereby to support the wringer head. The finder but-

ton is of larger diameter than notches 16, so that it cannot pass therethrough. As the button is moved out of any of notches 16 by a manual torque exerted on the head, the conical form of the finder button cams the head upwardly on column 8, the bottom of the button then moving slidably on the upper face of the index plate, as indicated in FIG. 7, until it again enters the next of notches 16.

A vertical operating shaft 44 is disposed rotatably in the wringer head housing coaxially with drive shaft 6, being journalled at its upper end in top wall 24 of the body member, as at 46, and being journalled adjacent its lower end in bottom wall 26 of the housing, as at 48, and being secured against longitudinal movement by retainer pin 50 (see FIG. 1). The lower end of operating shaft 44 extends downwardly into socket 38, and is provided at its extreme lower end with a transverse slot 52 in which the upper end of drive shaft 6 is slidably engaged. Thus the operating shaft is driven by the drive shaft, but is free to move vertically when the wringer head is elevated by finder button 40 as previously described.

Carried for free rotation on shaft 44 within the housing are a pair of confronting bevel gears 54 and 56. Said gears mesh respectively with diametrically opposite portions of a bevel gear 58. Gear 58 is rotatable about a horizontal axis at right angles to shaft 44, having a hub member 60 journalled in a tubular bearing 62 formed integrally with inner end wall 20 of the housing. The outer end of hub 60 is socketed at 64 to receive non-rotatably therein the extended axle 66 of a wringer roll 68 which, together with a companion roll 70 urged thereagainst by resilient means, not shown, is carried by a wringer assembly indicated generally by the numeral 72 and mounted on wringer head 18 by any suitable means. Thus rotation of bevel gear 58 will cause operation of the wringer rolls 68 and 70 in the usual and well-understood manner.

A clutch member 74 is carried for longitudinal sliding movement on shaft 44 between bevel gears 54 and 56, but is secured against rotation thereon by key 76. Said clutch member is provided at its upper end with axially projecting lugs 78 adapted when the clutch member is moved upwardly to mesh with axially projecting lugs 80 of gear 54, whereby gears 54 and 58 are turned to rotate wringer roll 68 in one direction. The clutch member is provided at its lower end with axially projecting lugs 82 adapted when the clutch member is moved downwardly to mesh with axially projecting lugs 84 of gear 56, whereby gears 56 and 58 are turned to rotate wringer roll 68 in the opposite direction. When the clutch member is at the midpoint of its vertical travel, its lugs 78 and 82 do not engage the lugs of either of bevel gears 54 or 56, and wringer roll 68 is not turned. This is the neutral position.

Clutch member 74 is moved between its neutral and its two drive positions by a control shaft 86 coaxial with bevel gear 58 and carried rotatably in a tubular bearing 88 formed integrally with outer end wall 22 of the housing. At its inner end, within the housing, shaft 86 carries a flat cam 90 in a plane at right angles to its axis. A crank pin 92 projects from the inner face of said cam in parallel but eccentric relation to shaft 86. A rectilinear bearing block 94 carried rotatably on crank pin 92 is engaged slidably in a peripheral groove 96 formed in clutch member 74. Shaft 86 is turned manually by means of a handle 98 affixed to the outer end thereof externally of the housing. Thus as handle 98 is turned 90 degrees in either direction from its neutral position, bearing block 94 moves clutch member 74 selectively upwardly or downwardly to engage the lugs thereof with either gear 54 or gear 56, as previously described. Preferably, handle 98 is hollow, and is provided with internal webs 100 and 102 (see FIG. 2) which cooperate with a stop member 104 formed integrally with housing end wall 22 to limit turning of handle 98 to 90 degrees in either direction from its neutral position.

As best shown in FIG. 3, cam 90, which turns with shaft 86, is substantially oval in shape, having rounded indentations

106 and 108 formed in the periphery thereof along its minor axis, and similar indentations 110 and 112 formed in the periphery thereof along its major axis. A vertical locking pin 114 is disposed within the wringer head housing parallel to drive shaft 6 and on the diametrically opposite side thereof from finder button 40. Said pin is carried for axial sliding movement in a bearing 116 formed in bottom wall 26 of the housing, and extends downwardly therefrom through a tubular member 118 formed integrally with the housing. Adjacent its lower end, said pin is supported slidably in a washer 120 pressed into the lower end of tubular member 118. The upper end of the locking pin is rounded to engage the peripheral edge of cam 90, and is urged upwardly against said cam by a spring 122 coiled about said pin within tubular member 118, said spring bearing at its lower end against washer 120 and at its upper end against a rod 124 inserted transversely through the locking pin.

The length of locking pin 114 is such that when cam 90 is in its neutral position, with cam indentation 108 engaging the upper end of the locking pin, and when finder button 40 is in full engagement with one of the notches 16 of index plate 14, as shown in FIGS. 1-3 and 6, the lower end of the locking pin also extends into one of notches 16, but only to such an extent that it will still be elevated diagonally out of said notch when the head is turned manually about column 8 to change the indexed position of the head, the diagonal elevation being caused by the conical form of finder button 40 as it cams the head upwardly. When the head is between index positions, with finder button 40 riding on the upper surface of the index plate, as indicated in FIG. 7, the lower end of locking pin 114 is disposed just slightly above the index plate. However, when finder button 40 is positioned in one of notches 16 and handle 98 is turned in either direction to clutch the head, and engaging the upper end of locking pin 114 in either of indentations 110 or 112 of cam 90, cam 90 forces the locking pin downwardly against spring 122, causing it to enter a notch 16 of index plate 14 more deeply, as shown in dotted lines in FIG. 6. The locking pin cannot thereafter be elevated from the notch by the action of finder button 40, but will strike the side wall of its notch, and the head is thus locked against free rotation on column 8 as a result of reactive force from the driving power of drive shaft 6, which as previously noted can and frequently does result in injury by causing the wringer assembly to strike persons standing nearby. For example, if laundry should become jammed between wringer rolls 68 and 70 so that bevel gear 58 can turn only with difficulty, or not at all, the head and wringer assembly could be caused by the power of drive shaft 6 to spin freely about column 8, sometimes under the full power of the washing machine motor.

55 The structure thus far described is well known and in extremely common usage. However, while the interconnection between the clutching means and the locking means as shown and described provides nominally that the clutch cannot be engaged except when the head is locked against rotation on column 8, the structure is not foolproof and can still permit free rotation of the head, with its attendant danger, under at least two general sets of circumstances which frequently occur. First, an operator may turn handle 98 to engage the clutch while 60 the head is disposed intermediate two of its index positions with finder button 40 riding on the top surface of index plate 14. In this instance, the lower end of locking pin 114 crowds downwardly against the index plate, elevating the head to a still higher point, as in FIG. 8. This permits the clutch to be fully engaged with the head not locked against rotation, so that said head can be rotated rapidly about column 8 by the reactive power of drive shaft 6. Moreover, if the head rotates rapidly 65 enough, the lower end of the locking pin may pass over notches 16 of the index plate without entering them, so

that the head can continue to rotate indefinitely. Second, when the head is elevated on column 8 by finder button 40 in normal operation, it may for a variety of reasons fail to fall by gravity when said finder button is again positioned over a notch 16 of the index plate, but will remain elevated, with the result again that handle 98 may be turned sufficiently to engage the clutch before the locking pin is fully engaged in a notch of the index plate. To mention only a few of the reasons that the head may not drop to engage the finder button in the index plate, the upper end portion of column 8 may become bent or malformed, or be over-sized as relates to the size of socket 38, or become so fouled with dirt, grit or grime, as to fit too tightly in socket 38 to allow the head to fall normally by gravity. Also, drive shaft 6 may become so bent, corroded, or fouled by grit and grime as to fit so tightly in slot 52 of shaft 44, that the head cannot drop normally by gravity. Also, shaft 44 itself may be bent. Also, unavoidable variations in dimensions of parts due to manufacturing tolerances sometimes contribute to a like malfunction. It is to the elimination of any possibility of free rotation of the wringer head on column 8 under these and other circumstances that the present invention is directed.

To this end, stop members 126 are provided on the inner surface of skirt 34 of the wringer housing, which cooperate with stop members 128 carried by index plate 14. Stop members 128 consist of radially projecting fingers each formed at the edge of the index plate integrally therewith and intermediate a pair of notches 16 of said index plate. Hence there are eight stops 128, and they are equally spaced angularly of the index plate. Stops 126, four in number as shown, each consist of a finger struck out of a cylindrical plate 130 of spring steel or the like which is fitted snugly into skirt 34, said last named fingers projecting radially inwardly so that the circular orbit thereof overlaps the outer ends of stops 128. Stops 126 could also be rigidly affixed to or integral with skirt 34, but for convenience of manufacture are made as parts of cylinder 130 which may be inserted when the housing is otherwise completed. As shown, cylinder 130 is provided at its upper end with a pair of inturned, diametrically opposite ears 132 which are affixed to the wringer head housing by screws 134. Cylindrical plate 130 is thus rigidly and permanently fixed in position.

It will be noted in FIGS. 1, 3, 5 and 6 that when the wringer head is normally indexed with finder button 40 firmly resting in one of index plate notches 16, stops 126 are disposed at a lower level than stops 128, each of stops 126 being disposed directly beneath one of stops 128. Then, as the head is diagonally elevated by the finder button, stops 126 are also elevated and each enters between a pair of stops 128, but does not engage stops 128. Also, if at the new index position the head falls normally by gravity to engage the finder button in another of notches 16, stops 126 will again drop below the level of stops 128 without engaging them. Hence, as long as the head is free to rise and fall normally on column 8 under the cam action of finder button 40, stops 126 and 128 remain inoperative.

However, if the head should stick or jam with the bottom of the finder button at the level of the top surface of the index plate, as in FIG. 7, and the clutch engaged, or if the clutch is engaged with the head intermediate index positions so that the head is still further elevated by the downward force of locking pin 114 against the top surface of the index plate, as in FIG. 8 both as previously discussed, the resultant turning of the head about column 8 will be arrested by engagement of stops 126 against stops 128, as shown in FIGS. 7 and 8. The head will thus be stopped and locked against further rotation, and will remain so locked until the fault is corrected. For example, in FIGS. 7 and 8 it will be seen that the stops 126 and 128 arrest rotation of the head with said head nearly in an index position, so that the head may fall by

gravity, or may be forced down by manual force, to engage locking pin 114 in one of notches 16. In any event, the head cannot again be turned about column 8, nor can it be spun about freely by re-engaging the clutch, until it is again lowered on column 8 to move stops 126 below stops 128, and this downward movement allows locking pin 114 to reassume its normal function.

Of course, a single stop 126 and a single stop 128 would eventually arrest undesired rotation of the head, but this might allow nearly a complete revolution of the head before the stops engaged, and injury to a bystander might occur during this movement. For this reason, a stop 128 is provided between each consecutive pair of notches 16 of the index plate, so that the head cannot rotate more than one-eighth of a revolution under the circumstances described before the stops engage to arrest rotation. It is virtually impossible that it could build up sufficient momentum to cause injury in such a short arc of movement. The same limitation of movement could be provided by using one stop 128 and eight stops 126. Of course, the maximum number of sets of stops which can be used is a number equal to the number of notches 16 in the index plate. Four stops 126 are used, although a greater or smaller number could be used if desired, in order that if one of them should break or bend, there will be others to perform the function desired.

In the modification of the device shown in FIGS. 9-11, all parts and operations are identical to the species shown in FIGS. 1-8, corresponding parts bearing corresponding numerals, except that stops 136, which correspond to stops 126 of FIGS. 1-8, are of triangular cross-sectional contour about axes radial to column 8, each having upwardly converging top surfaces 138 and 140, as best shown in FIGS. 10 and 11. Stops 136 as shown constitute solid blocks welded or otherwise suitably affixed to cylindrical member 130, although they also could be formed by tabs cut from the member 130 if desired, in much the same manner as stops 126 in FIGS. 1-8.

The operation of the species of FIGS. 9-11 is also the same as that in FIGS. 1-8, except that in addition it will be seen that whenever the wringer head 18 tends to be rotated by the reactive force of drive shaft 6, as discussed in connection with the species of FIGS. 1-8, and stops 136 are thus brought into engagement with stops 128 of the index plate, the inclined faces 138 or 140 of stops 136 act as cams tending to force head 18 downwardly to its normal position. This tends additionally to correct the very defect or misuse which caused the malfunction originally. For example, assuming that the rotation of the head was caused by turning handle 98 to clutch the head when said head is between index positions, the downward cam action of stops 136 on the head will tend to force locking pin 114 upwardly into the head, allowing the head to fall, provided that cam 90 has not already been turned sufficiently to fix the locking pin immovably in its lowered position. If the head was jammed in an elevated position by bending, malformation, or poor fit of parts, or by fouling of parts by corrosion, grit or grime, all as discussed above, then the cam action of stops 136 may jar it loose and allow said head to drop normally. Of course, if the cam effect of stops 136 does not succeed in lowering the head on column 8 as just described, said stops still act to arrest rotation of the head positively, just as do stops 126 in the species of FIGS. 1-8.

While I have shown and described certain specific embodiments of my invention, it will be apparent that many minor changes of structure and operation could be made without departing from the spirit of the invention as defined by the scope of the appended claims.

What I claim as new and desire to protect by Letters Patent is:

1. For use in connection with a wringer assembly having horizontal rolls and adapted to be operated by a rotatably driven vertical drive shaft, a fixed tubular column coaxial with and enclosing said drive shaft, a planar index

plate secured concentrically to said column in spaced relation from the upper end thereof, said index plate being notched at regularly spaced intervals around the edge thereof, and a wringer head carrying the wringer assembly, said wringer head comprising a housing having a socket formed in the lower portion thereof which fits for rotary and vertical movement on the upper end portion of said column, said housing including a hollow cylindrical skirt surrounding said index plate, a finder button fixed in said housing and adapted to engage successively by gravity the notches of said index plate as said housing is rotated on said column, said finder button being conically bevelled whereby said housing is elevated on said column when said finder button is moved intermediate any successive pair of notches of said index plate, a driving connection carried in said housing between said drive shaft and said wringer assembly, a clutch operable to selectively engage, disengage, or reverse said driving connection, a shaft carried rotatably by said housing and adapted when turned to operate said clutch, a cam fixed to said clutch shaft, a locking pin carried for vertical movement by said housing, resilient means carried by said housing and urging said locking pin against said cam, whereby when said clutch shaft is turned to move said clutch to either of its operative positions, said locking pin will be extended downwardly to a position with its lower end below said finder button, whereby to enter one of the notches of said index plate to lock said housing against rotation on said column, said locking pin being so positioned that it can enter a notch of said index plate only when said finder button is aligned with another of said notches, a safety device comprising:

- (a) a radially outwardly projecting stop carried by said index plate in the plane thereof and enclosed by said skirt, and
- (b) a radially inwardly projecting stop affixed to said skirt, the radius of the orbit of the inner end of said skirt stop being less than radial dimension of the outer end of said index plate stop, said skirt stop being disposed at a lower elevation than said index plate stop when said finder button is engaged in any one of said index plate notches, but being elevated into the plane of said index plate whenever said housing is elevated either by the cam action of said finder button on said index plate when said housing is rotated, or further elevated by the downward crowding action of said locking pin against said index plate if said clutch should be engaged with said finder button intermediate any successive pair of notches of said index plate, whereby interengagement of said stops will arrest and prevent rotation of said housing at either of said elevated positions.

2. The combination as recited in claim 1 wherein said skirt stop is disposed directly beneath said index plate stop when said finder button is engaged in a notch of said index plate, whereby as said housing is elevated diagonally

by the cam action of said finder button on said index plate as said housing is rotated on said column, said skirt stop will be elevated into the plane of said index plate without engaging the stop of the latter.

- 5 3. The combination as recited in claim 1 wherein said index plate is provided with a plurality of radially outwardly projecting stops at regularly spaced angular intervals.
- 10 4. The combination as recited in claim 1 wherein the skirt is provided with a plurality of radially inwardly projecting stops at regularly spaced angular intervals.
- 15 5. The combination as recited in claim 1 wherein both said index plate and said skirt are provided with a plurality of stops as described, the stops of each member being disposed at regularly spaced angular intervals.
- 20 6. The combination as recited in claim 1 wherein both said index plate and said skirt are provided with a plurality of stops as described, the stops of each member being disposed at regularly spaced angular intervals, and wherein each of said skirt stops is disposed directly beneath one of said index plate stops when said finder button is engaged in a notch of said index plate, whereby as said housing is elevated by the cam action of said finder button or said index plate as said housing is rotated on said column, said skirt stops will be elevated into the plane of said index plate without contacting the stops of the latter.
- 25 7. The combination as recited in claim 1 wherein the interengaging surfaces of the stops of said skirt and said index plate are planar, vertical, and disposed generally radially to the axis of rotation of said housing on said column.
- 30 8. The combination as recited in claim 1 wherein the stops of said skirt and said index plate are formed to provide a cam action tending to force said housing downwardly on said column whenever said fingers are brought into engagement with each other by rotation of said housing on said column.
- 35 9. The combination as recited in claim 2 wherein said skirt stop is essentially triangular about its radial axis, having two surfaces converging upwardly symmetrically to a vertical axis, whereby as said stop is brought into engagement with said index plate stop by rotation of said housing on said column in either direction, said skirt stop will act as a cam tending to force said housing downwardly on said column.
